UNITED STATES PATENT OFFICE.

WALTER M. BARBER, OF SPRINGFIELD, MASSACHUSETTS.

DESIGN FOR A SIDEWALK PUMP-CASING.

45,737.

Specification for Design.

Patented May 12, 1914.

Application filed December 5, 1913. Serial No. 804,939. Term of patent 14 years.

To all whom it may concern:

Be it known that I, WALTER M. BARBER, a citizen of the United States, residing at Springfield, in the county of Hampden and State of Massachusetts, have invented a new, original, and ornamental Design for a Sidewalk Pump-Casing, of which the following is a specification, reference being had to the accompanying drawing, forming part thereof.

Figure 1 is a front elevation, Fig. 2 is a

side elevation, and Fig. 3 is a perspective view of a sidewalk pump casing showing my new design.

I claim:

The ornamental design for a sidewalk pump casing, as shown.

WALTER M. BARBER.
